UNITED STATES PATENT OFFICE.

JOHN V. HEMSTREET, OF HERKIMER, NEW YORK.

TYPE-WRITER CABINET.

SPECIFICATION forming part of Letters Patent No. 613,270, dated November 1, 1898.

Application filed May 2, 1898. Serial No. 679,492. (No model.)

To all whom it may concern:

Be it known that I, JOHN V. HEMSTREET, a citizen of the United States, residing at Herkimer, in the county of Herkimer and State of New York, have invented new and useful Improvements in Type-Writer Cabinets, of which the following is a specification.

My invention relates to that class of cabinets for type-writers which embody a swinging shelf for supporting the machine and one or more springs arranged to cushion the downward movement of the shelf when the cabinet is closed and assist in the upward movement of the shelf when the cabinet is opened.

15 The general object of the invention is to provide a shelf cushioning and raising spring designed more particularly for use in the cabinet disclosed in the Letters Patent of Michael Foley, dated September 21, 1897, and numbered 590,540; and it consists in the peculiar and advantageous construction and arrangement of parts hereinafter described, and particularly pointed out in the claims appended.

In the accompanying drawings, which illustrate the preferred embodiment of my invention, Figure 1 is a transverse section of a type-writer cabinet embodying my invention with the lid closed and the machine-shelf and other parts in the position they assume when the lid is closed. Fig. 2 is an elevation of the opposite side of the side wall shown in Fig. 1 with the movable arm of the spring illustrated by full and dotted lines in the positions it assumes when the shelf is down and up, respectively. Fig. 3 is an enlarged broken perspective showing in detail a portion of the side wall, the shelf and lateral arm thereof, and the spring arranged to be engaged by said arm.

40 In the said drawings similar letters designate corresponding parts in all of the several views, referring to which—

A is the side wall of a type-writer cabinet, which is similar to and equipped like the opposite wall. (Not shown.)

B is the lid.

C is the swinging machine-shelf.

D is a swinging bracket connected to shelf C and pivotally connected with the side wall A.

45 E is a lever fulcrumed at *a* on the wall A and having the short arm *b* connected by a link *c* with the bracket D and the long arm *d* pivotally connected with the shelf C.

The parts thus far described are similar in

construction and arrangement to the corresponding parts of the Foley patented construction aforesaid. Consequently when the lid is moved rearwardly and downwardly by the operator until it assumes a vertical or approximately vertical position the swinging shelf C will, through the medium of lever E, link *c*, and bracket D, be raised and moved forwardly to a horizontal position, so as to carry the machine into close proximity to the operator sitting at the cabinet. Also the leverage afforded by lever E and bracket D will enable the operator to move the lid to its vertical position and raise the shelf to its horizontal position with but a minimum amount of effort, and the lever will also enable the lid to retain the shelf in its horizontal position when the machine is on said shelf without the aid of any auxiliary weight. This is due to the fact that when the shelf C is raised to its horizontal position the fulcrum-point *a* of lever E and the pivotal connection of said lever to the link *c* will rest in the same or approximately the same horizontal plane and the further fact that a rearward movement must attend the downward movement of the shelf. Such rearward movement of the shelf is effectually prevented by the arrangement of the fulcrum *a* of lever E and the pivotal connection of said lever to link *c* in the same horizontal plane when the shelf is in a horizontal position, and consequently the shelf cannot be lowered until the lid is raised to move the arm *b* of the lever and thereby move the pivotal connection of said lever to the link *c* downwardly from the horizontal plane of the fulcrum *a* of the lever.

40 F are drawer-cleats on the side of the wall A opposite to that shown in Fig. 1.

G is the spring for cushioning the downward movement of the shelf and assisting in the raising of the same, which spring is preferably arranged at the drawer side of the wall A. H is a curvilinear slot in wall A, and I is an arm or lateral projection on the shelf C, which extends through the slot H and is raised to engage one leaf or arm *e* of the spring G. The said spring G is preferably of the construction shown in Figs. 2 and 3—that is to say, it comprises the body-coil *f*, which terminates at one end in an arm or leaf *g*, which is connected to a block *h* on one of the drawer-cleats F or is otherwise connected with the side wall A and the arm or

leaf *e* aforesaid, which is arranged to be engaged by the lateral projection *I* of the shelf *C*. The spring *G* is of such size and strength and is so arranged that when it is spent or 5 expanded to its fullest extent its arm *e* will rest in the position shown by dotted lines in Fig. 2, and the arm or projection *I* on the shelf *C* is so arranged that when the shelf *C* is in its horizontal position and the fulcrum 10 *a* of lever *E* and the pivotal connection of said lever to the link *c* are in the same horizontal plane it will rest in the position shown by dotted lines in Fig. 2—that is to say, beyond and out of engagement with the arm *e* 15 of the spring. In virtue of this it will be observed that the operator is enabled to raise the lid *B* and move the arm *b* of the lever *E* to carry the pivotal connection of said lever to the link *c* downwardly from the horizontal 20 plane of the fulcrum *a* before the projection *I* of the shelf impinges against the leaf *e* of the spring and the said shelf is subjected to the pressure of or cushioned by the spring. This is an important advantage, for it will be 25 readily perceived that if the spring were arranged to bear against the arm *I* of the shelf when said shelf is in its horizontal position it would be exceedingly hard for the operator by raising the lid *B* to move the arm *b* of the 30 lever *E* to carry the pivotal connection of the same to the link *c* downward from the horizontal plane of the fulcrum *a* and move the shelf rearward and downward, as described. The relative arrangement of the projection 35 *I* of the shelf and the spring *G* when the shelf is in its horizontal position is also advantageous, because the spring is relieved of pressure and is at rest, which materially conduces to its durability.

40 In practice when the shelf is lowered and the projection *I* reaches and engages the spring *G* the spring will cushion the shelf and prevent the same from dropping back suddenly in the event of the operator losing control of the lid. The spring or springs approximately balance the shelf and the machine thereon when said shelf is half-way down in the well of the cabinet, and in consequence they will not only cushion the downward movement of the shelf, but will assist in the upward movement of the same.

Having thus described my invention, what I claim is—

1. In a type-writer cabinet, the combination 55 with the side wall of the cabinet, a machine-shelf pivotally connected with said wall and having an arm projecting through a curvilinear slot in said wall, a lid, a lever fulcrumed at an intermediate point of its length 60 on the side wall of the cabinet and having a long arm pivotally connected with the lid, and a link connected with the shelf and pivotally connected with the lever in advance of the fulcrum-point thereof, the whole being so 65 arranged that, when the shelf is raised to its horizontal position, the pivotal connection of the lever to the link and the fulcrum-point

of said lever will rest in the same or approximately the same horizontal plane with the former in advance of the latter; of a spring 70 connected with the cabinet and having an arm or leaf arranged in the path of the arm of the shelf; said spring being of such size and strength and being so arranged that when the shelf is in its horizontal position, its said arm or leaf will rest in advance of and out of engagement with the arm of the shelf, substantially as specified.

2. In a type-writer cabinet, the combination with a side wall having a curvilinear slot, a machine-shelf pivotally connected with the side wall and having an arm projecting through said slot, and a lid, said shelf and lid being connected together and with the side wall substantially as described; of a spring 85 for cushioning the downward movement of the shelf and assisting in the upward movement thereof; said spring having an arm or leaf designed to be engaged by the arm of the shelf and being of such size and strength and 90 so arranged that, when the shelf is in its horizontal position, the said arm or leaf will rest in advance of and out of engagement with the arm of the shelf, as set forth.

3. In a type-writer cabinet, the combination with a side wall of a cabinet, a machine-shelf pivotally connected with the wall, a lid, a lever fulcrumed at an intermediate point of its length on the side wall of the cabinet and having a long arm pivotally connected with 100 the lid, and a link connected with the shelf and pivotally connected with the lever in advance of the fulcrum-point thereof, the whole being so arranged that when the shelf is raised to its horizontal position the pivotal connection of the lever to the link and the fulcrum-point of said lever will rest in the same or approximately the same horizontal plane with the former in advance of the latter; of a spring disposed in the path of the shelf for cushioning 110 the downward movement and assisting in the upward movement thereof; the said spring being entirely spent and idle and resting out of engagement with the shelf when the same is in its horizontal position, substantially as 105 specified.

4. In a type-writer cabinet, the combination with a side wall, a machine-shelf, and a lid, said shelf and lid being connected together and with the side wall substantially as 120 and for the purpose described; of a spring disposed in the path of the shelf for cushioning the downward movement and assisting in the upward movement thereof; the said spring being entirely spent and idle when the shelf 125 is in its horizontal position, substantially as specified.

In testimony whereof I have hereunto set my hand in presence of two subscribing witnesses.

JOHN V. HEMSTREET.
